TELEVISION LAMP

Byon E. Elb, Solano County, Calif. (1825 Sonoma Blvd., Apt. 110, Vallejo, Calif. 94590)

Filed Sept. 23, 1971, Ser. No. 183,301

Term of patent 14 years

Int. Cl. D26—05
U.S. Cl. D48—20

FIG. 1

FIG. 2

FIG. 1 is a front perspective view of the television lamp embodying my invention;

FIG. 2 is a rear perspective view thereof.

The cord is broken away to indicate indeterminate length.

I claim:

The ornamental design for a television lamp, substantially as shown and described.
